[57] CLAIM

The ornamental design for a portable infant's hair washing seat, as shown and described.

DESCRIPTION

FIG. 1 is a perspective view of a portable infant's hair washing seat, looking from the front and top, showing my new design;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1; and,

FIG. 7 is a bottom plan view of FIG. 1.

The play bar and play elements shown in broken line in FIG. 1 are for illustrative purposes only, and are not part of the claimed design.
